UNITED STATES PATENT OFFICE.

WILLIAM H. CAPELLEN AND EARLE M. CAPELLEN, OF MORGAN TOWNSHIP, FRANKLIN COUNTY, IOWA.

COMBINED METAL FRAME AND CLOSURE.

1,363,717.

Specification of Letters Patent. Patented Dec. 28, 1920.

Application filed August 26, 1919. Serial No. 319,900.

To all whom it may concern:

Be it known that we, WILLIAM H. CAPELLEN and EARLE M. CAPELLEN, citizens of the United States of America, and residents of Morgan township, Franklin county, Iowa, have invented certain new and useful Improvements in Combined Metal Frames and Closures, of which the following is a specification.

Our invention relates to improvements in combined metal frames and closures, and the object of our improvements is to furnish a metal lining frame for a wall opening, and a metal closure for the opening of the frame, both integrally reinforced and otherwise supported for permanent construction.

This object we have accomplished by the means which are hereinafter described and claimed, and which are illustrated in the accompanying drawings, in which Figure 1 is a perspective view of part of a wall constructed of bricks or blocks, showing a wall opening supplied with our improved lining frame and combination two-part metal doors; Fig. 2 is an enlarged horizontal section of one of the blocks forming a part of the jamb for said opening; Fig. 3 is an elevation of a like lining frame combined with a pair of metal doors hinged to the opposite parts of said frame; Fig. 4 is an enlarged horizontal section of a jamb-block and a modified form of lining frame secured thereon; Fig. 5 is an outside elevation of our lining frame as constructed to line a wall opening for a window; Fig. 6 is an enlarged horizontal section of a block or jamb showing another modified form of lining frame fixed thereon; Fig. 7 is a vertical cross section of a hollow tile sill supplied with our improved lining frame, and Fig. 8 is a modified form of the same; Fig. 9 is a perspective fragmentary detail view showing the spread apart joint of the flanges of a bent lining frame, and Fig. 10 is a similar view, including the gusset connections for said spread apart joints.

Similar numerals of reference denote corresponding parts throughout the several views.

The lining frame for either a door or window opening and a wall 15 is constructed as follows:

An elongated plate of metal of the requisite thickness, is first cut or slotted crosswise from opposite edges a short distance, with

the slits alined transversely, and then the longitudinal marginal parts 2 of this plate 1 are bent in the same direction at right angles from the face of the plate, and then the plate parts 1 are bent transversely in line with the slits to spread apart the flanges 2 angularly at the location of said slits 3 as shown in said Fig. 9. The parts of the flanges 2 adjacent to the open or spread apart joints 3 are supplied with a number of rivet holes 4, and gusset plates 5 are placed to cover said joints. The gusset plates are then fixedly secured to the flanges 2 by means of rivets 6 passed through holes in the gusset plates and through the alined holes 4 in said flanges. This affords a very light but rigid lining frame for the wall opening, and for a door lining frame such as shown in Fig. 3, and not having a sill, the lining frame has a sill covering part 75 omitted.

In the type of door opening shown in Fig. 1, and in the window opening shown in Fig. 5, the outwardly troughed lining frame is of the rectangular closed type including the part covering the sill. The opposite flanges 2 and 3 are secured to the adjacent part of the wall 15 by a cross bolt 7 passed therethrough and through a joint of the wall, and provided with a fastening nut 80 16. The web part 1 of the lining frame may be longitudinally crimped outwardly at 8 and 9 as shown in Fig. 2, which reinforces and strengthens the frame and one or more of said projecting crimps serve as 85 backing or abutments for a door such as the double flap door 10-13 displayed in Fig. 1 swinging on hinges 14 mounted on one of the jamb parts of the frame and in which the flaps are arranged one above another, or where the flaps 17 and 18, as shown in Fig. 3, are independently hinged to opposite jamb-parts of the frame, side by side, to swing toward each other with their free edges secured in closed position by a hasp 90 19. The door flaps are made of metal, such as sheet iron, are preferably provided with a plurality of parallel spaced crimps 11 of V or other section, to stiffen and strengthen them, and the flaps are additionally supported by means of cross-bars 12 which may be angle-bars, as shown, or of other well known shapes.

In the lining frame modification shown in Fig. 4, one of the longitudinal crimps 20 is 110

formed on the flange 2 and serves as a door stop.

In the lining frame for window-sash, shown in Fig. 6, the longitudinal crimps 23 and 24 are turned inwardly toward the jamb and lintel as both reinforcing and spacing means. That part of the lining frame which is mounted about the sill block 15, as shown in Fig. 7, is offset at 25, providing a drainage slope 26, and in the variation shown in Fig. 8, said drainage slope 26 is carried outwardly from the sill, then bent reversely down at 27 and 28 to supply a ledge for delivering drippings beyond the wall.

The type of double flap doors, shown in Fig. 1, is suitable for a stable, while the type shown in Fig. 3 may be used in a garage or other structure.

20 The window sash 21—22 fit within the web 1 of the lining frame and against the longitudinal stop 9.

The lining frame and the doors shown may be considerably varied in form and dimensions and yet be within the scope of our invention which contemplates the provision

of these parts for convenient assemblage with the wall openings of buildings.

Having described our invention, what we claim as new, and desire to secure by Let- 30 ters Patent, is:

1. A lining frame for a wall opening, consisting of an elongated plate bent at places to inclose the adjacent parts of the wall, and longitudinally crimped to provide 35 a plurality of differently directed closure-stops which are respectively directed parallel with, and at an angle to said wall.

2. A lining frame and closure for a wall opening, consisting of a metal lining for the 40 parts of the wall bounding said opening, having a plurality of differently positioned and directed longitudinal outwardly-projecting crimps, a metal closure swingingly mounted on said lining to close its opening 45 and formed with numerous parallel stiffening integral crimps.

Signed at Waterloo, Iowa, this 7th day of Aug., 1919.

WILLIAM H. CAPELLEN.
EARLE M. CAPELLEN.
